VAPORIZER HEAD UNIT

Lawrence Katzman, New York, and Meyer Block, Port Washington, N. Y., and Irvin J. Gershen, Springfield, N. J., assignors to Kaz Manufacturing Co., Inc., New York, N. Y., a corporation of New York

Application April 18, 1957, Serial No. 45,790

Term of patent 14 years

(Cl. D83—1)

Fig. 1 is a front perspective view of a vaporizer head unit embodying our new design;

Fig. 2 is a rear perspective view of said unit;

Fig. 3 is a top plan view thereof; and

Fig. 4 is a front view thereof.

We claim:

The ornamental design for a vaporizer head unit, as shown.
